(57) **CLAIM**

The ornamental design for a child's chair, as shown and described.

DESCRIPTION

The subject matter of this application may have common inventorship with and/or may be related to the subject matter of the following:

U.S. application Ser. No. 13/353,327, titled "Groove System for Adjustable Chair," filed by Khai Gan Chuah on Jan. 19, 2012, and issued as U.S. Pat. No. 8,960,788 on Feb. 24, 2015;

U.S. application Ser. No. 29/503,311, titled "Cushion for Highchair," filed by Khai Gan Chuah on Sep. 25, 2014, and issued as U.S. Pat. No. D780498 on Mar. 7, 2017;

U.S. application Ser. No. 29/555,077, titled "Adjustable Infant Highchair," filed by Khai Gan Chuah on Feb. 18, 2016, and issued as U.S. Pat. No. D779842 on Feb. 28, 2017;

U.S. application Ser. No. 29/710,694, titled "Leg Holder for Chair," filed by Khai Gan Chuah on Oct. 25, 2019, and issued as U.S. Pat. No. D962754 on Sep. 6, 2022; and, U.S. application Ser. No. 29/710,879, titled "Adjustable Chair," filed by Khai Gan Chuah on Oct. 28, 2019.

This application incorporates the entire contents of the foregoing applications herein by reference. All the material from the U.S. applications which is essential to the claimed design is included in this application. Amendments of the claim may be based on the content of the incorporated material. However, with or without a specific amendment, it is understood that any material in the U.S. applications which is not present in this application forms no part of the claimed design.

FIG. 1 is a perspective view of a child's chair showing my new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

(Continued)

The broken lines shown in the drawings illustrate unclaimed features or environmental structures and form no part of the claimed design.
